UNITED STATES PATENT OFFICE.

SZYMON H. LESNIKOWSKI, OF DETROIT, MICHIGAN.

WARDROBE-TRUNK.

1,129,211.

Specification of Letters Patent. Patented Feb. 23, 1915.

Application filed June 20, 1914. Serial No. 846,339.

To all whom it may concern:

Be it known that I, SZYMON H. LESNIKOWSKI, a subject of the Czar of Russia, residing at Detroit, in the county of Wayne 5 and State of Michigan, have invented certain new and useful Improvements in Wardrobe-Trunks, of which the following is a specification.

This invention relates to certain new and 10 useful improvements in wardrobe trunks.

An object of the present invention is to provide in a single device a combined wardrobe and trunk which may be used as a trunk while traveling, and be easily and 15 quickly set up to a wardrobe position when it is desired that the clothes be suspended from the upper wall.

A further object of the invention is to provide a combined wardrobe trunk formed 20 of a plurality of telescoping sections which may be easily and quickly distended to assume the position of a wardrobe and be effectively retained in such position while the device may be as easily collapsed to present a 25 trunk construction with the usual hinged cover.

A further object of the invention is to provide a wardrobe trunk of three sections arranged in vertical alinement, the middle 30 section telescoping within the lower section while the front, rear and end walls of the upper section are adapted to be folded into the top wall of the upper section when the device is in position as a trunk, there 35 being provided at each of the four corners of the device, telescoping members in the form of rods and tubes which are positively held in either of their extended or telescoped positions.

With the above general objects in view 40 and others that will appear as the nature of the invention is better understood, the same consists in the novel construction, combination and arrangement of parts to be hereinin 45 after more fully described and then claimed.

In the accompanying drawings forming a part of this application and wherein like designating numerals refer to corresponding parts throughout the several views: 50 Figure 1 is a perspective view of the device in position as a wardrobe. Fig. 2 is a perspective view of the device in position as a trunk. Fig. 3 is an inverted perspective view of the upper section of the device removed. 55 Fig. 4 is a view showing in perspective the several telescoping tube and rod sections.

Fig. 5 is a detail sectional view of the hinge joint formed by the telescoping rod when the device is in position as a trunk, with the trunk cover partially open. Fig. 6 is a detail perspective view of a portion of the lower section. Fig. 7 is a detail perspective view of a portion of the bottomless middle section. Fig. 8 is a vertical longitudinal sectional view of a portion of the device in 60 position as a wardrobe. Fig. 9 is a side elevational view partly in section of the end wall of the middle section, showing in side elevation the mechanism for holding the parts in either distended or collapsed position, and, Fig. 10 is a side elevational view 65 partly in section of the device positioned as a trunk, showing the middle section telescoped within the lower section and the side and end walls of the upper section folded 70 into the cover wall. Fig. 11 is a detail 75 sectional view of the hinge joint formed by the telescoping rod when the device is in position as a trunk, with the trunk cover partially open.

Briefly described, the invention embodies in a single device a convertible wardrobe and trunk and consists preferably of three sections arranged in vertical alinement, the 80 middle section adapted to telescope within the lower section while the front, rear and end walls of the upper section are adapted to be folded into the cover of the upper section, as shown in Fig. 5, when the device is 85 collapsed, the said cover to be supported on the middle and lower sections. The device is preferably rectangular in plan view with a telescoping rod or tube at each corner of the sections with means operating in connection with the rods and tubes and carried by the end walls of the several sections to hold the same in either of the distended or collapsed positions.

Referring more in detail to the accompanying drawings, the reference letter A designates in general the lower section, B the middle section, C the upper section, and D the cover for the upper section. The lower section A is of box-like construction similar 95 in form to a trunk and comprises in detail the bottom wall 10, the front and rear walls 11 and end walls 12, the lower section A being supported on suitable roller casters 13. False doors 14 are provided in connection 100 with the front wall of the lower section, which front wall constitutes the front wall of the trunk when the device is in use as such, and when in use as a wardrobe, the front wall of the lower section is of course 105 always closed. The several sections are 110 preferably rectangular in plan view and at

each corner of the bottom section on the inner face, the same is provided with a vertically-disposed slot and received in each of the slots at each corner is the tubular member 15 as shown in detail in Fig. 4, this tubular member 15 being provided with a slot 16 extending substantially the whole length of the tube. An opening 17 is formed adjacent the upper end of each of the tubes 15 10 for purposes to be later described.

The middle section B is formed of the rear wall 18 and end walls 19, with the front wall constituting a double door 18', the free edges of which meet in the middle 15 of the section. This section is bottomless as shown in Figs. 7 and 8 and is rectangular in plan view, the length and width of which is slightly less than the bottom section A so that the same may telescope into the bottom 20 section. Secured to each corner of the section B at the upper edge by the single strap 20 and at the lower edge by the V-shaped strap 21 which embraces the side and end walls of the section is a tubular member 22 25 provided with an opening 23 adjacent each end thereof. Each corner of the section B is provided with one of these tubular members 22, which tubular members are adapted to telescope within the tubular members 30 15 carried by the four corners of the bottom section A, the tube sections 22 being limited in their upward movement by the V-shaped strap 21 engaging the closed upper end of the slot 16 but permitting a free vertical 35 movement of the said tube 22 within the slotted tube 15.

The upper section C comprises side and end walls hinged to the cover D, the rear wall being indicated 24, the end walls 25, 40 and the front wall comprising the double door sections 26. These doors 26 are hinged to the upper section C in vertical alinement with the hinge joint for the doors 18' carried by the middle section, with the meeting 45 edges of the double doors also being in vertical alinement. In the folded or collapsed condition of the upper section C when the device is used as a trunk as shown in Fig. 2, the rear wall 24 is first swung inwardly on its hinge connection with the cover D, after 50 which the end walls 25 are moved inwardly and the door sections 26 folded on to the end walls 25, the several parts being held in their folded position by fastening means, such as 55 straps 27. The upper inner face of the cover D is provided with parallel strips 28 which carry a conventional form of clothes hanger 29, as clearly illustrated in Fig. 3. In order to hold the upper section C and cover D in 60 extended position as shown in Fig. 1, and also to permit the cover carrying the folded side, end and door sections as shown in Fig. 5, to hinge to the middle section, I provide 65 the form of telescoping rods disclosed in Fig. 4 and designated 30 and 31, the rod 30

being provided with an opening 32 adjacent its lower end while the rod 31 is provided with similar openings 33 adjacent each end. The rod 30 is provided with a hinged extension 34 adapted to be received and retained 70 in sockets 35 formed in the corners of the cover section D, two of the rod sections 30 being employed and constituting the hinge member by which the cover section D is pivoted, while the other side of the cover section 75 D is supported on a pair of tubes 31, the rods 30 and tubes 31 being received and telescoping in the tube sections 22 at each corner of the middle section D.

Means are provided to hold the several 80 sections in either wardrobe position as shown in Fig. 1 or in trunk position as shown in Fig. 2, such means being carried by the end walls of the bottom, middle and upper section and comprises in detail, in forming in the said end walls a recess 36 having an extension opening 37 for the reception of a pin 38 normally spring-pressed outwardly as at 39 and passing through the upper edge of the end sections as at 40. Pivoted 85 mounted as at 41 in the recess 36 is a pair of opposing links 42, these links having a pin and slot connection at their lower ends as at 43 with the pin 38 and having connected to the outer ends thereof as at 44, 90 the horizontally-disposed sliding bolts 45 projecting laterally of the end walls. The projecting ends of the bolts 45 are adapted to be received in selective openings 17, 23, 32, and 33 to hold the several sections in 95 wardrobe position as shown in Fig. 1 or in trunk position as shown in Fig. 2.

In the position shown in Fig. 1, the several sections have been extended with the 100 projecting bolts 45 of the locking mechanism carried by each section passed through the 105 openings in the tube and rod sections 15, 22, 30, and 31, which will hold the sections in locked extended condition for use as a wardrobe. Any suitable means could be provided to enable the door sections 26 and 18' of the 110 middle and upper sections to move in unison, although the same may be easily independently operated. In this position, the side and end walls of the upper section C have been unfolded from the cover D which will 115 present for use the hooks 29 carried by the inner wall of the cover D.

To cause the several sections to assume the position shown in Fig. 2, the side and end walls and door sections of the upper section C are folded as shown in Fig. 5 and held in such position by the fastening member 27, after which the several button extensions 40 carried by each section are operated 120 to release the sliding bolts 45 from the openings in the tube and rod sections, such operation permitting the middle section B to telescope within the lower section, with both the middle and lower sections consti- 125 130

tuting a support for the cover D. The device as now presented, is in trunk form, and the cover D is permitted to swing on the hinged extensions 34 of the rods 30 when the push button 40 of the upper section releases the sliding bolt 45 from the opening 33 in the upper end of the upper tube section 31. It will be seen that the cover C is pivoted to the device in a manner similar to 10 a trunk, the lock for the cover being the sliding bolt disposed in the end walls of the upper section, although any other conventional form of locking means may be employed.

15 While the drawings show the preferred embodiments of the invention, I do not wish to be confined to the exact details of construction, as various forms, modifications and arrangement of the parts as shown may 20 be had without departing from the spirit and scope of the invention as claimed.

What I claim as new is:—

1. A wardrobe trunk comprising a plurality of sections, the section adjacent the 25 bottom adapted to telescope within the same, the side and end walls of the upper section adapted to be folded and be supported on the two lower sections, and coöperating means carried by each section arranged to 30 hold the trunk in either distended or telescopic condition.

2. In a wardrobe trunk, a lower section, a middle section and an upper section, a cover carried by the upper section, the side and 35 end walls of the upper section adapted to be folded into the cover, means for holding the same in folded position, telescopic members carried by the corners of the several sections, and means associated with said telescopic members adapted to hold the trunk in either distended or telescopic condition.

3. In a wardrobe trunk, a plurality of sections, each section comprising side and end walls, telescopic members carried by the 45 corners of each section, and spring-pressed sliding bolts carried by the end walls of each section and adapted to engage the

telescoping members to hold the same in adjusted position.

4. In a wardrobe trunk, a plurality of sections, telescoping rods carried by each section, the sections adapted to be moved to trunk position, and means for releasing two of the telescoping members from the upper section to permit the same to be hinged. 55

5. In a wardrobe trunk, a lower section, a middle section, an upper section, and a cover, tubular members mounted in the corners of the lower section, tubular members having strap connections with each corner 60 of the middle section and adapted to telescope within the tubular members in the lower section, tubular members carried by the upper section and telescoping within the tubular members carried by the middle section, two of the tubular members carried by 65 the upper section having a hinged connection with the cover whereby the same may be pivotally-mounted.

6. In a wardrobe trunk, a plurality of sections, telescopic guides carried by the corners of each section, spring-controlled locking bolts carried by the end walls of each section arranged to engage the telescopic guides to hold the sections in either distended or telescopic condition, and means for releasing said bolts from the guides to raise 75 and lower the sections.

7. In a wardrobe trunk, a lower section, a middle section, an upper section, and a cover, 80 telescopic guides between the sections, two of the guides carried by the upper section having a hinge joint adjacent the cover, means for holding the sections in either distended or telescopic condition, and means for releasing the front edge of the cover to 85 permit the same to swing on the rear hinged telescoping members.

In testimony whereof I affix my signature in presence of two witnesses.

SZYMON H. LESNIKOWSKI.
